[57] CLAIM

The ornamental design of a wireless communications terminal, as shown and described.

DESCRIPTION

FIG. 1 is a perspective view of one embodiment of the wireless communications terminal, showing a first and a second display screen;

FIG. 2 is a top plan view of the wireless communications terminal of FIG. 1;

FIG. 3 is a front elevational view of the wireless communications terminal of FIG. 1;

FIG. 4 is a side elevational view of the right side of the wireless communications terminal of FIG. 1;

FIG. 5 is a rear elevational view of the wireless communications terminal of FIG. 1;

FIG. 6 is a bottom plan view of the wireless communications terminal of FIG. 1;

FIG. 7 is a front elevational view of the wireless communications terminal of FIG. 1 showing exemplary displays on the first and second display screens when the terminal is "on". The dashed lines and associated characters showing the exemplary displays do not form a part of the claimed design;

FIG. 8 is a perspective view of a second embodiment of the wireless communications terminal, showing a single display screen. The dashed lines showing push buttons do not form a part of the claimed design;

FIG. 9 is a top plan view of the wireless communications terminal of FIG. 8;

FIG. 10 is a front elevational view of the wireless communications terminal of FIG. 8;

FIG. 11 is a side elevational view of the right side of the wireless communications terminal of FIG. 8;

FIG. 12 is a rear elevational view of the wireless communications terminal of FIG. 8;

FIG. 13 is a bottom plan view of the wireless communications terminal of FIG. 8; and,

FIG. 14 is a front elevational view of the wireless communications terminal of FIG. 8, showing an exemplary display on the display screen when the terminal is "on". The dashed lines and associated characters showing the exemplary display do not form a part of the claimed design.
